UNITED STATES PATENT OFFICE.

HARRY A. DAVIS, OF HOPE DALE, MASSACHUSETTS, ASSIGNEE TO DRAPER COMPANY,
OF HOPE DALE, MASSACHUSETTS, A CORPORATION OF MAINE.

LENO OR CROSS-WEAVING LOOM.

1,160,266.

Specification of Letters Patent. Patented Nov. 16, 1915.

Application filed March 26, 1914. Serial No. 827,301.

To all whom it may concern:

Be it known that I, HARRY A. DAVIS, a citizen of the United States, residing at Hopedale, county of Worcester, and State 5 of Massachusetts, have invented an Improvement in Leno or Cross-Weaving Looms, of which the following description, in connection with the accompanying drawings, is a specification, like characters on the 10 drawings representing like parts

The invention to be hereinafter described relates to looms for weaving leno or cross-woven fabrics, and more particularly to such looms as are adapted to produce fabrics 15 having alternating cross and plain woven portions.

The aims and purposes of the present invention are to provide a loom of the above general character which shall be simple in 20 construction, effective and reliable in operation, and wherein the change from plain to cross weaving and vice versa may be readily controlled by simple means operating in desired relation with other parts of the loom.

25 These and other objects of the present invention will best be made clear from the following description and accompanying drawings of one form of means for carrying the invention into practical effect, it being understood that the invention is not limited to the particular construction shown 30 and described, but in its true scope is clearly defined by the claims.

In the drawings: Figure 1 is a side elevation of a loom embodying one form of the present invention, some of the parts of the loom being omitted for clearness of illustration of those features having to do more particularly with the present invention; 35 Fig. 2 is an enlarged detail showing among other features, one form of means for controlling the change from plain to cross-weaving and vice versa; Fig. 3 is a detached detail showing the treadle actuating means 40 for the heddles; Fig. 4 is a detached detail illustrating a part of the two treadles and the connection between the means for controlling the change from plain to cross-weaving and the heddle hook, to be 45 described; and Fig. 5 represents the treadles in cross-section, the means for connecting

them with the heddles, and illustrating by dotted lines different positions of the parts.

Mounted upon the loom frame 1, which may be of any desired form or construction suitable as a support for the usual moving parts of the loom, is the lay 2 having the usual reed, and sustained upon the lay swords 3 pivotally mounted at their lower ends upon the cross-shaft 4. The lay is 50 given its "beat up" movement by appropriate means, such as the usual crank shaft and connections, which, being well known by those skilled in the art, need not be herein illustrated and described. The "take-up" mechanism for taking up the cloth as 55 it is woven may likewise be of any appropriate character operated by or through the lay movements, that shown in the present 60 form of the invention comprising a sand or take-up roll 5, Fig. 1, having operative connection through the gears 6, 7, 8, 9 and 10, Fig. 1, with a ratchet wheel 11, the teeth of which are adapted to be engaged by a pawl 12 pivotally mounted at 13 to a bracket 14 65 carried by the lay sword. A spring 15, Fig. 2, normally maintains the pawl in position to engage the teeth of the ratchet wheel 11, the construction being such that as the 70 lay moves back and forth the pawl will impart a step-by-step take-up movement to the ratchet wheel in the direction of the arrow, Fig. 2, and through the gearing connection 75 described or other operative connection will cause the sand or take-up roll 5 to take up 80 the cloth as it is woven. As the cloth is thus taken up, it may be wound upon a suitable cloth roll, but as such roll and its connection with the take-up form no part of 85 the present invention, and are well understood by those skilled in the art, they need not be herein further described. The gearing 90 connection between the ratchet wheel 11 and the sand or take-up roll forms a good 95 form of means for taking up the cloth through the step-by-step movement of the pawl 12, but it is to be understood that any form of transmitting connection may be employed.

Rising from the loom frame 1 is the support 16, Fig. 1, for the arms 17 carrying a shaft or rod 18 provided with the pulleys 19

about which pass the straps 20 connected at 21 to the heddles 22 and 23, the construction being such that as one heddle is pulled down it will, through the straps 20, cause 5 the other heddle to rise. A spring 24 connected to one of the heddles at 25 and to a fixed part, as at 26, normally acts to depress the heddle to which it is connected, the construction being such that should the 10 heddle 23, for instance, be depressed it will cause the other heddle 22 to be raised, and when the heddle 23 is permitted to rise, the spring 24 will act to depress the heddle 22 and perforce, cause the heddle 23 to be 15 lifted.

Each of the heddles has a series of fingers, each provided with an eye through which a warp thread *a* is passed, so that as the heddles are raised and lowered as above described, alternate warp threads will be raised and lowered for the formation of the shed. This construction of heddles is well understood by those skilled in the art, and is indicated by dotted lines at 27, Fig. 1.

25 In cross-weaving looms, as is well known, the warp threads or "ends," as they are sometimes called, are given a relative lateral or transverse movement to cause one warp thread to cross over an adjacent warp 30 thread after the heddles have been relatively moved vertically to permit, and then the relative vertical movement of the heddles is reversed to form the shed to receive the weft or filling thread. In plain weaving, however, this transverse movement of the heddles 35 does not take place, it being only necessary to relatively move the heddles vertically, in the case of vertical looms, to form the shed for the weft or filling thread. These characteristic movements of the heddles in plain 40 and in leno or cross-weaving are well understood by those skilled in the art.

In the present form of the invention the lateral or transverse relative movement of 45 the heddles is secured from a rock shaft 28, Fig. 1, sustained by suitable bearings and provided with side projecting portions 29 constituting a rocker arm bearing upon the heddle frames 22 and 23. A similar rocker 50 arm may be pivotally mounted on the support 16 at the opposite side of the loom to bear upon the heddle frames so that as one frame is moved transversely in one direction, the other heddle frame will be correspondingly moved transversely in the opposite 55 direction, substantially as in Patent No. 994,018, May 30, 1911. Secured to the rock shaft 28 is an arm 30, Fig. 1, operatively connected by an arm 31 to an appropriate 60 cam 32 mounted on the cam shaft 33; said arm 31 being pivoted at 34 and having a projection 35 engaging the cam 32, the construction being such that as the cam 32 rotates with the shaft 33, which is operated 65 from a suitable source of power and in

proper timed relation with other parts when leno or cross-woven fabric is being woven, the rock shaft 28 is rocked upon its longitudinal axis, thereby imparting the proper and desired relative lateral or transverse 70 movement to the heddles or heddle frames 22 and 23, as will be readily understood.

Suitably mounted at the rear part of the loom is a counter shaft 36 carrying the cams 37 and 38 which are laterally or transversely 75 arranged to act upon the rolls 39, one carried by each of two treadles or levers 40 and 41, pivotally mounted at 42, Figs. 1 and 3, upon a suitable bracket 43 secured to the loom frame. Since the cams 37 and 38 act upon the 80 two treadles, as will presently appear, they may, for convenience of identification, be hereinafter referred-to as the treadle cams.

The counter shaft 36 may be driven from any suitable source, but as shown it is in 85 driving connection with the cam shaft 33 through the gears 44, 45, and 46, the gear 45 being an idler or transmission gear between gears 44 and 46 on the shafts 33 and 36 respectively.

As hereinbefore noted, the heddles or heddle frames 22 and 23 are connected by the straps 20 so that upon movement of one, a corresponding movement is imparted to the other in the reverse direction, and said heddles are normally under the action of the spring 24, tending to lower the heddle or heddle frame 22. In the present invention means are provided for connecting both treadles 40 and 41 to one of the heddles or heddle frames, in the present instance the heddle or heddle frame 23, whereby leno or cross weave may be produced, and to interrupt the connection between one of said treadles and the heddle at desired times, whereby plain weave may be produced, the result being that the fabric will contain portions of leno or cross weave and portions of plain weave.

In the present form of the invention the treadle 41 is connected to the heddle 23 by the flexible strap 47, one portion of which is secured to the saddle or collar 48, which may be adjustably connected to the treadle 41 by means of a suitable set screw 49, the other portion of the flexible strap 47 being connected to the heddle 23 in any suitable manner, substantially as indicated in Fig. 3. Inasmuch as the connection between the treadle 41 and the heddle 23 is to remain undisturbed during the weaving operation, this connection may be denominated a permanent connection. Pivotally connected at 50 to the heddle 23 is the hook or similar device for detachably connecting said heddle with the other treadle 40. In the present form of the invention the hook is preferably formed of an upper and lower member connected by a screw-threaded turnbuckle 51, whereby the length of the connection between the heddle 125

23 and the treadle 40 may be regulated, as desired. The upper member 52 of the hook device is preferably hinged or pivotally connected to the heddle 23, and the lower member 53 is provided with a shoulder or hook 54, Fig. 5, for engagement at desired times with the treadle 40, substantially as indicated in Fig. 5.

Means are contemplated by the present invention for controlling engagement and disengagement of the treadle 40 with the heddle 23, and to this end the hook, hereinbefore described, is adapted for detachable connection with the treadle 40. Inasmuch as the treadle 40 is at times to be disconnected from the heddle 23, a spring 55 is provided which normally maintains the end of the treadle 40 in raised position.

Mounted for movement transversely of the loom and consequently in a direction transverse to the length of the treadle 40, is a slide 56 which passes through a fixed abutment 57, Fig. 4, and has a flattened head portion 58 provided with a perforation through which passes the member 53 of the hook, substantially as indicated in Fig. 4. Disposed between the abutment 57 and the head 58 of the slide member 56 is a spring 59 normally acting to move the slide 56 and force, the hook, in a direction to cause the hook to engage beneath the treadle 40, substantially as indicated by full lines in Fig. 5.

From the construction described thus far, it will be apparent that when the spring 59 is permitted to act, it will cause the head 58 to carry the hook or shoulder 54 below the treadle 40, and when moved in the opposite direction will withdraw the hook or shoulder 54 from the path of the treadle 40.

Various means may be employed for controlling the movement of the slide 56 and head 58, but the present invention contemplates so controlling the slide 56 that on a predetermined number of picks the change from leno or cross weave to plain weave and vice versa, may be effected.

As a further feature of the invention, also, means are provided for stopping the take-up during the time that the plain weave is being produced, thereby securing increased strengthening quality from the plain-woven portion of the fabric, a condition which becomes of great importance when weaving certain kinds of leno or cross-woven fabrics of light character, such as mosquito-netting, and the like.

As one form of means to the above ends, the slide 56, Fig. 4, is connected to one arm 60 of a bell crank lever pivoted at 61, preferably upon the rock shaft 28, Fig. 1, the bell crank being supported thereon loosely between two collars 62. The other end 63 of the bell crank is connected to an arm 64 extending to and connected with a controller

65, Figs. 2 and 4. In order that the controller 65 may appropriately move the bell crank and consequently the slide 56, the desired distance to cause the shoulder or hook 54 to be placed in or withdrawn from the path of movement of the treadle 40, the said controller 65, Fig. 2, is provided with a series of holes 66, to any one of which the actuator 64 may be connected, as indicated in Fig. 2. The controller 65 is pivotally mounted at 67, Fig. 2, and has a bearing portion 68 adapted to rest upon a pattern chain, as will now be described.

Mounted upon a shaft or stud 69 supported by the loom frame, is a sprocket wheel 70, Fig. 2, to which is connected for rotative movement therewith a ratchet wheel 71. The teeth of the ratchet wheel are adapted to be engaged by a pawl 72 carried by an arm 73 loosely mounted for rotative or oscillatory movement about the axis of the ratchet wheel, substantially as indicated by dotted and full lines in Fig. 2. The oscillatory member 73 carrying the pawl 72 is connected to an arm 74, at 75, the other end portion of the arm 74 being suitably connected at 76 to a projection 77 adjustably mounted in a rocker arm 78 rising from the shaft 4, substantially as indicated in Fig. 2. The rocker arm 78 is connected to the sword 3 which carries the lay and partakes of the movement thereof. One form of means for securing this movement of the rocker arm 78 with the sword would be to secure the sword 3 and the rocker arm 78 fixedly to the cross shaft 4, the latter having rocking movements in its bearing. This would be a good, practical form of this structure, but it is to be understood that the construction may be varied in detail, the essential in this respect being that the rocker arm 78 be movable with the lay or lay sword, and consequently impart to the ratchet wheel 71 a step-by-step movement corresponding to the back-and-forth movement of the lay. This connection of the rocker arm for movement with the lay enables the step-by-step movement of the ratchet 71 and its connected sprocket 70 to be in timed relation with the picking action of the loom, as will readily appear.

In order that the projection 77 may be properly adjusted on the rocker arm, the latter may be provided with a slide 79 having a slot 80 in which the bolt 81 secured to the projection 77 may be moved to adjust the projection 77 as desired. If preferred, a similar adjustment of the slide 79 may be made by means of a slot 82 and bolt 83. These details may, of course, be widely varied, their purpose being to give to the pawl 72 a proper step-by-step movement as the lay moves back and forth, and various details of means to this end will suggest themselves to those skilled in the art.

Mounted for rotative movement with the sprocket wheel 70 is a star wheel 84, Fig. 2, having portions 85 to receive a roll 86 mounted on the arm 87, the upper end of which is under the influence of the spring 88, the construction being such that the roll 86 and star wheel 84 under the yielding action of the spring 88, normally prevent accidental or too free movement of the sprocket wheel 70, and also prevent reverse movement thereof as the pawl 72 is drawn to the left.

The pattern chain, which as a whole may be designated 89, may comprise any usual form of such device,—in the present form of the invention it is indicated as a sprocket chain having plain link and riser portions at intervals. The plain link portions 90 are pivotally connected together as indicated in Fig. 2, and when such portions are beneath the part 68 of the controller 65, the actuator 64 will be held to the left, Fig. 2, by the spring 59, Fig. 4, whereby the hook or shoulder 54 will be permitted to assume the position in the path of the treadle 40, substantially as indicated by full lines in Fig. 5. When the treadle 40 is thus connected to the heddle 23, the loom produces cross weave, as hereinbefore indicated, so that as long as the plain link portions 90 of the pattern chain are passing beneath the part 68 of the controller 65, the loom will continue to weave leno or cross-woven portions. As hereinbefore noted, however, it is desirable at times to strengthen the fabric by forming therein plain-woven portions, and to this end the pattern chain 89 is provided at intervals with risers 91, Fig. 2, which, as they pass beneath the part 68 of the controller 65, will swing the controller outward, or to the right, Fig. 2, thereby withdrawing the slide 56 against the stress of the spring 59, and moving the shoulder or hook portion 54 of the hook to the left, Fig. 5, to left-hand dotted line position, whereupon the loom will weave a number of plain picks corresponding to the number of risers on the pattern chain. When the plain portions 90 of the pattern chain again pass beneath the part 68 of the controller, the slide 56 under the action of the spring 59, will again place the shoulder 54 of the hook in the path of the treadle itself, whereupon leno or cross-weaving operations will be resumed.

As indicated in Fig. 2, the pattern chain is passed about the sprocket wheel 70 and is given its step-by-step forward movement through the ratchet and pawl, as hereinbefore described, so that the fabric being produced will have leno or cross-woven portions and plain-woven portions, alternately, for a predetermined number of picks, dependent upon the number of plain and riser portions on the pattern chain. In order to

maintain the pattern chain in proper operative relation to the sprocket wheel 70, the looped end of the chain, that to the left, Fig. 2, may be carried around an idler 92, suitably supported on an arm 93.

From the construction described, it will be apparent that both treadles are connected to the same heddle while producing leno or cross-woven portions of the fabric, and during such time each of these treadles acts under the operation of its respective cam 37, 75 38 to move the heddles relatively in a vertical direction; whereas, in weaving plain portions of the fabric one of the treadles is disconnected from the heddle, whereupon the other treadle alone acts under the operation of its cam to raise and lower the heddles relatively for the formation of the shed. It will be further noted that the number of picks, either of leno or of plain portions in the fabric may be varied according to the desire of the designer or the character of fabric to be produced.

It is sometimes desirable to stop the take-up during the formation of the plain-woven portions of the fabric in order to give increased strengthening value to such plain portions, and as one form of means to this end, the present invention contemplates disconnecting the actuating means for the take-up from the part operated by it when leno or cross-weaving ceases and plain weaving is initiated, and to restore this operative connection between the take-up and its actuating means, when plain weaving ceases and leno or cross-weaving is started. In the present form of the invention the controller 65 is provided with a pawl trip arm 94, Fig. 2, said trip arm being appropriately secured to the controller by suitable means such as the nut and threaded portions 95, the other end of said arm being passed through a loop 96 secured to the pawl 12 which normally actuates the ratchet wheel 11 of the take-up. The end of the pawl trip arm 94 has an abutment or is turned as at 97, the construction being such that when the controller 65 is moved to the right, Fig. 2, this being the time when plain portions are to be woven, the pawl trip arm 94 acts upon the pawl 12 and disengages it from operative relation with the ratchet wheel 11. This condition of affairs prevails while the series of risers 91 act upon the controller, and when these risers have passed the part 68 of the controller, and the latter resumes its bearing upon the low links of the pattern chain, the arm 94 moves to the left, thereby permitting the spring 15 to restore the pawl 12 into operating relation with the take-up.

While the invention has been described in connection with certain details of structure in carrying the invention into practical effect, it is to be understood that the inven-

tion is not limited to these details, but may be varied within its true scope, as defined by the claims; and I believe I am the first in the art to provide in a loom of the character described, means for connecting two cam-operated treadles to a single heddle or heddle frame for producing leno or cross-weaving, and means for interrupting or detaching the connection between one of the treadles and the heddle for the production of plain weave, either with or without interrupting the take-up during the production of the plain portions.

What is claimed is:—

1. In a leno or cross-weaving loom, the combination of heddles for controlling the warp threads, treadles for operating the heddles, means for relatively moving the heddles transversely, means for permanently connecting one heddle to one of the treadles, and means for automatically connecting and disconnecting the same heddle and the other treadle.

2. In a leno or cross-weaving loom, the combination of a pair of heddles for controlling the warp threads, means connecting said heddles to cause movement of one to be imparted to the other in the opposite direction, a pair of cam-operated treadles, means for connecting both treadles to the same heddle for the production of leno or cross-weave, means for relatively moving the heddles transversely, and means acting automatically to disconnect one of the treadles from said heddle for the production of plain weave.

3. In a leno or cross-weaving loom, the combination of a pair of heddles for controlling the warp threads, means for relatively moving the heddles transversely, means connecting said heddles to cause movement of one to be imparted to the other in raising and lowering the warp threads, a pair of treadles and operating means therefor, permanent connections between one of said treadles and one of said heddles, means for detachably connecting the other treadle to the same heddle, and means for automatically controlling said last-named means to cause the same to be operatively connected with or disconnected from said heddle.

4. In a leno or cross-weaving loom, the combination of a pair of heddles for controlling the warp threads, a pair of treadles and operating means therefor, means for connecting both treadles to the same heddle for producing leno or cross-weave, means for relatively moving the heddles transversely, and means acting automatically after a predetermined number of picks for interrupting the connection of one of said treadles with said heddle for the production of plain weave.

5. In a leno or cross-weaving loom, the

combination of a pair of heddles for controlling the warp threads, a pair of treadles and operating means therefor, means for connecting both treadles to the same heddle for producing leno or cross-weave, means for relatively moving the heddles transversely, and means acting automatically after a predetermined number of picks for interrupting the connection of one of said treadles with said heddle for the production of plain weave, said last-named means also acting after a predetermined number of plain picks to restore the connection between the said treadle and heddle.

6. In a leno or cross-weaving loom, the combination of two heddles for controlling the warp threads, means for relatively moving the heddles transversely, a take-up for taking up the fabric as woven, two treadles and operating means therefor, means for connecting both of said treadles to the same heddle and means acting automatically to disconnect one of the treadles from said heddle and to stop the take-up.

7. In a leno or cross-weaving loom, the combination of two heddles for controlling the warp threads, means for relatively moving the heddles transversely, a take-up, two treadles, means for connecting both treadles to the same heddle, and means operative after a predetermined number of picks to interrupt the connection between one of said treadles and said heddle and stop the take-up.

8. In a leno or cross-weaving loom, the combination of two heddles for controlling the warp threads, means for relatively moving the heddles transversely, a take-up, two treadles, operating means therefor, means for connecting both treadles to the same heddle, and means operative after a predetermined number of picks to interrupt the connection between one of said treadles and said heddle and stop the take-up and operative thereafter to restore said connection and start the take-up.

9. In a leno or cross-weaving loom, the combination of a pair of heddles, means for relatively moving them transversely, a pair of treadles, a permanent connection between one treadle and a heddle, a hook device for detachably connecting the other treadle to the same heddle, and means for causing the hook to engage its treadle and be operated in producing leno or cross-weave, and for causing the hook to be disengaged from its treadle for producing plain weave.

10. In a loom, the combination of two heddles, means for relatively moving the heddles transversely, two treadles and operating means therefor, a strap permanently connecting a treadle to one heddle, a hook device for connecting the other treadle with the same heddle, and means acting auto-

matically for connecting and disconnecting the hook device and its treadle.

11. In a loom, the combination of two heddles, two treadles and operating means therefor, a strap connecting a treadle to one heddle, a hook device for connecting the other treadle with the same heddle, means for relatively moving the heddles transversely and means acting automatically for connecting and disconnecting the hook device and its treadle, a take-up, means for operating the take-up while the treadles are connected operatively with the same heddle, and means for rendering said take-up means inoperative when the hook device is disconnected from its treadle.

12. In a leno or cross-weaving loom, a pair of heddles, a strap connection between the heddles, a spring connected to one heddle and normally acting to move the heddles relatively, a pair of treadles, means for connecting both treadles to the other heddle for the production of leno or cross-weave, means for relatively moving the heddles transversely, and means for detaching the connection of one treadle to said heddle for the production of plain weave.

13. In a leno or cross-weaving loom, a pair of heddles, a strap connection between the heddles, a spring connected to one heddle and normally acting to move the heddles relatively, a pair of treadles, means for connecting both treadles to the other heddle for the production of leno or cross-weave, means for relatively moving the heddles transversely, means for detaching the connection of one treadle to said heddle for the production of plain weave, a take-up, a device for operating the take-up during leno or cross-weaving, and means for rendering said device ineffectual during plain weaving.

14. In a leno or cross-weaving loom, the combination of a pair of heddles connected for simultaneous movement in opposite directions for separating the warp threads, a spring acting on one heddle, means for relatively moving the heddles transversely, a pair of treadles, a permanent connection between the other heddle and one of said treadles, a hook for detachably connecting the same heddle to the other treadle, a take-up including a ratchet and pawl, means for controlling the engagement and disengagement by the hook with its treadle, and means for rendering the ratchet and pawl inoperative when the hook is disconnected from its treadle.

15. In a leno or cross-weaving loom, the combination of two heddles and two treadles, a permanent connection between one heddle and one treadle, a detachable connection between the same heddle and the other treadle, means including an element

having high and low portions for controlling said detachable connection, means for causing said element to continue the connection between said other treadle and the heddle for the production of leno or cross-weave for any desired number of picks and to detach said connection and maintain it detached for the production of plain weave for any desired number of picks, and means for relatively moving the heddles transversely.

16. In a leno or cross-weaving loom, the combination of two heddles and two treadles, a permanent connection between one heddle and one treadle, a detachable connection between the same heddle and the other treadle, means including an element having high and low portions for controlling said detachable connection, means for causing said element to continue the connection between said other treadle and the heddle for the production of leno or cross-weave for any desired number of picks and to detach said connection and maintain it detached for the production of plain weave for any desired number of picks, means to suspend the take-up during the production of plain weave, and means for relatively moving the heddles transversely.

17. In a leno or cross-weaving loom, the combination of two heddles and two treadles, a permanent connection between one treadle and one heddle and a detachable connection between the other treadle and the same heddle, means for relatively moving the heddles transversely, means including a chain for controlling the detachable connection, a take-up, a pawl for operating the take-up, devices for actuating the chain and take-up pawl and means for rendering the take-up pawl ineffectual for producing take-up of the fabric when the chain detaches the detachable connection.

18. In a leno or cross-weaving loom, a pair of heddles connected to move in opposite directions for raising and lowering the warp threads, a pair of treadles, permanent connections between one of said treadles and one heddle, a hook for detachably connecting the other treadle to the same heddle, means acting normally to establish operative connection between the hook and said other treadle for the production of leno or cross-weave for any desired number of picks, means for relatively moving the heddles transversely, and means operative at intervals to withdraw the hook from such operative relation with said treadle for the production of plain weave for any desired number of picks.

19. In a leno or cross-weaving loom, the combination of heddles for controlling the warp threads, treadles for operating the heddles, means for relatively moving the

heddles transversely, means for permanently connecting one heddle to one of the treadles, means for detachably connecting the same heddle to the other treadle, and 5 means to stop take-up when the said heddle is detached from said other treadle.

In testimony whereof, I have signed my

name to this specification, in the presence of two subscribing witnesses.

HARRY A. DAVIS.
